UNITED STATES PATENT OFFICE.

JACOB RICHARD FRANCIS, OF FLINT, MICHIGAN.

MEANS FOR HEATING INTAKE MANIFOLDS FOR INTERNAL-COMBUSTION ENGINES.

Application filed October 26, 1917. Serial No. 198,685.

To all whom it may concern:

Be it known that I, JACOB RICHARD FRANCIS, a citizen of the United States, residing at Flint, in the county of Genesee and State 5 of Michigan, have invented certain new and useful Improvements in Means for Heating Intake Manifolds for Internal-Combustion Engines, of which the following is a specification, reference being had therein to the accompanying drawing.

This invention relates to certain new and useful improvements in means for heating the intake manifold of an internal combustion engine and more particularly to means 15 for controlling the fluid heating medium, as it has been found in practice owing to the heavy non-volatile fuels, called by the trade, gasoline distillate, motor fuel, etc., now in general use for internal combustion engines, 20 that it is necessary to use heat to aid in volatilizing the fuel portion of the mixture of the charge in order to obtain a satisfactory combustion of the explosive charge within the internal combustion engine, and it is 25 particularly desirable to have a large volume of heated fluid applied to the charge in first starting and warming up the engine so as to obtain a more perfect combustion as early as possible and then to reduce the volume of 30 the heating fluid applied as otherwise the charge owing to the natural radiation of heat from the engine, will become too hot and the power of the engine will therefore be reduced.

I have found in practice in starting a cold engine with any of the above-mentioned fuels unless heat be applied to the outside walls of the intake manifold, a large percentage of the fuel fails to properly volatilize which causes incomplete combustion, and as a result the heavy part of the fuel is left on top of the piston after the combustion stroke of the engine, and this unburned portion of the fuel then finds its way past the 40 piston rings into the crank case and dilutes or thins the lubricating oil contained therein thus rendering the latter inefficient which causes undue wear on the bearings, of the crank-shaft piston, etc. This undesirable 45 result can be eliminated in starting a cold engine if the intake manifold be heated to the desired temperature as quickly as possible in order to pre-heat or more perfectly volatilize the heavy portions of the fuel of 50 the intake charge.

I am aware that I am not the first in the

art to heat the intake manifold of an internal combustion engine, but in prior devices the fluid heating medium was not under the control of the operator, and my invention 60 consists in providing means for controlling the application of the exhaust gases from the engine whereby I am able to obtain the desired result quickly by the use of a large volume of the exhaust gases from the engine 65 to heat the manifold for any desired period of time in connection with means for reducing or deflecting in part or completely the volume of exhaust gases so used.

Other and further objects and advantages 70 of the invention will be hereinafter set forth and the novel features thereof defined by the appended claims.

In the drawing I have shown a side elevation of a portion of a multiple cylinder internal combustion engine showing the application of my improved construction of heating means for the intake manifold in which 75 1 indicates the internal combustion engine, 2 the intake manifold which is connected to a throttle chamber of a carburetor, 3, in the usual manner in which the charge is mixed and delivered to the manifold from which it is drawn by the suction of the engine into the cylinders thereof. The engine is provided with the usual exhaust pipe 4 herein shown having two branches 5 and 6, the branch 5 being adapted to be connected to the muffler in the usual manner.

My invention consists in surrounding the 80 intake manifold 2 of the engine with a jacket 7 in order to provide a heating chamber surrounding the manifold whereby I am able to heat the manifold so as to obtain the desired result as will be hereinafter fully 85 described.

The heating jacket is provided with an inlet 8 of substantially the same size as the branch 6 of the exhaust pipe 4 to which is connected a valve casing 9 having a pivoted 90 valve 10 carrying an arm 11 which is connected to the lever 12 of the throttle valve 12' of the carburetor 3 by a link 13, said lever having a rod 14 extending to the dash for controlling the same in the usual manner. The throttle valve 12' of the carburetor 100 is so mounted and connected by the link 13 to the valve 10 that when the throttle valve of the carburetor is closed the damper or valve 10 is wide open, and when the throttle 105 valve of the carburetor is open the damper valve 10 is closed. Connected to the valve casing 110

9 is a conduit 15 carrying a valve casing 16 which is connected to the branch 6 of the exhaust pipe 4 and is provided with a valve 17 having a crank arm 18 for operating the 5 same to which is connected a rod 19 extending to the dash so as to be manually operated. The valve 17 is normally held closed by a coil spring 20 connected at one end to the arm 18 and at its opposite end to an eye 10 formed on the jacket 7 as clearly shown. The valve casing 16 is provided with a lug 21 carrying a set screw 22' arranged in the path of travel of the arm 18 by means of which the position of the valve 17 in respect 15 to its seat can be regulated.

The branch 5 of the exhaust pipe 4 has a pivoted valve or damper 22 mounted therein carrying an arm 23 to which is connected a rod 24 extending to the dash so as to be manually operated, said valve being normally held in open position by a coil spring 25 extending from the arm 23 to an eye formed on the jacket 7. The position of the valve 22 can be adjusted through the medium of adjusting screw 26 mounted in a lug 27, said screw being arranged in the path of travel of the arm 23 as clearly shown.

In the drawing the valve 22 is shown wide open and held in that position by the coil 30 spring 25 and by adjusting the set screw 26 so as to allow the arm further movement, the outlet branch 5 of the exhaust pipe 4 can be normally held partly closed. The jacket 7 is provided with an outlet 28 through which 35 the exhaust gases escape after they have circulated around the manifold.

From the foregoing description it will be seen that I have provided a pipe leading from the exhaust chamber of the engine to 40 the jacket surrounding the intake manifold having a valve actuated by a spring so as to normally hold said valve in closed position, said valve being manually operated and provided with means for adjusting the relative 45 position of the valve to its seat whereby the same may be normally held partly opened. In connection with this means for controlling the passage of exhaust gases to the heat jacket, I provide the other branch of the 50 exhaust pipe with a manually operated and adjustable valve which enables me to completely close this branch of the exhaust so as to cause the entire volume of exhaust gases 55 to pass out through the other branch into the conduit 15 from which they are discharged into the heat jacket so as to obtain a quick heating of the manifold when it is desired to start the engine.

It will be seen that these two valves or 60 dampers are manually operated and in order to provide means for further controlling the volume of initial heating fluid, I provide means for controlling the entrance of the exhaust gases into the jacket by a valve which 65 has a connection with the throttle valve of

the carburetor so that when the throttle is closed the valve is open and as the throttle valve is open the valve is closed, whereby means is provided for proportionately allowing the exhaust gases to enter the heat 70 jacket as the throttle is operated.

The operation of my improved construction of heating means is as follows: Assuming that the parts are in the position as shown and it is desired to start a cold engine, the manually operated rods 19 and 24 which are preferably controlled from the dash when used in connection with an internal combustion engine mounted in a vehicle, are shifted so as to close the branch 5 of the exhaust pipe 4 and open the branch 6 which allows the entire volume of exhaust gases to pass into the heating jacket so as to heat the manifold quickly in order to obtain a thorough combustion of the charge entering the cylinder, and as the heat of the engine increases the rod 24 is released which allows part of the exhaust gases to escape in their natural course. As the valve 17 is in open position a portion of the exhaust gases 90 will pass through the conduit 15 into the inlet of the jacket 7 and out the outlet 28 thereof of which will heat the manifold, and as the throttle is opened the passage of exhaust gases through the heating jacket is 95 regulated by the valve 10. By shifting the rod 19 the valve 17 will be adjusted so as to allow the desired proportion of the exhaust gases to enter the conduit 15 of the heating jacket 7.

I claim:

1. The combination with an internal combustion engine having an exhaust pipe, intake manifold, and carburetor connected thereto, of a heating jacket surrounding 105 said manifold, said exhaust pipe having a branch extending therefrom; a conduit connecting said branch to said heating jacket, a spring actuated valve mounted in said branch for controlling the admission of 110 heating fluid to said heating jacket, means for adjusting the relative position of said valve in respect to its seat for predeterminedly regulating the volume of exhaust gases admitted to said jacket, and a connection between said valve and the dash of the motor vehicle.

2. The combination with an internal combustion engine having an exhaust pipe, intake manifold and carburetor connected 120 thereto, of a heating jacket surrounding said manifold, a conduit extending from said exhaust to said jacket, a dash controlled valve for regulating the admission of heating fluid to said conduit from said exhaust, a spring 125 for normally holding said valve in partly closed position, and adjustable means for limiting the movement of said valve in one direction for setting said valve to govern the volume of gases admitted to said jacket. 130

3. An internal combustion engine having an exhaust pipe, intake manifold and carburetor connected thereto, said exhaust pipe having two branches, a heating jacket surrounding said manifold, a conduit extending from one branch of said exhaust to said jacket, a spring actuated valve mounted in said conduit for controlling the admission of heating fluid to said heating jacket, means for adjusting the relative position of said valves with respect to the seat for regulating the volume of exhaust gases admitted to said jacket and a dash controlled spring actuated valve mounted in the other branch of said exhaust for controlling the outlet of said exhaust whereby the entire volume can be diverted into the other branch to be delivered to the heating jacket.
4. An internal combustion engine having an exhaust pipe, intake manifold and carburetor connected thereto, means for throttling the explosive fluid, means for throttling the exhaust fluid, a heating jacket arranged to heat said manifold, a conduit extending from said exhaust to said heating jacket, a valve in said conduit having a connection with said carburetor throttling means and a dash controlled valve in said conduit preceding said throttle actuated valve for regulating the volume of exhaust gases passing through said conduit irrespective of the position of said throttle controlled valve.
5. The combination with an internal combustion engine, an exhaust passage and an intake passage communicating with said engine, a heater for the intake passage, means for supplying exhaust gases to said heater, a valve in said exhaust passage for throttling exhaust gases, means for operating said valve to increase the flow of exhaust gases to said heater, and a spring tending to open said valve when the latter is disengaged from its operating means.
6. The combination with an internal combustion engine having an exhaust passage and an intake passage in communication therewith, of a charge forming device for supplying explosive fluid to said intake passage having means for throttling the flow of explosive fluid, a heater for heating said intake passage, means for supplying exhaust gases from said engine to said heater, means for throttling the exhaust passage, a valve having a connection with said throttle valve for controlling the passage of exhaust gases to said heater and a second dash-controlled valve preceding said valve for controlling the volume of exhaust gases to said heater.
7. An internal combustion engine having an exhaust passage, intake manifold and carburetor connected thereto, a heating jacket for heating said manifold, a conduit extending from said exhaust pipe to said jacket, a valve in said exhaust pipe for throttling the exhaust gases for diverting said gases through said conduit, a throttle valve for said carburetor and a valve in said conduit having a connection with said throttle valve.
8. An internal combustion engine having an exhaust passage, intake manifold and carburetor connected thereto, a heating jacket for heating said manifold, a conduit extending from said exhaust pipe to said jacket, a valve in said exhaust pipe for throttling the exhaust gases for diverting said gases through said conduit, a charge forming device connected to said manifold having a throttle valve, a valve in said conduit having a connection with said throttle valve and a valve in said conduit preceding the throttle actuated valve for regulating the volume of exhaust gases passing through said conduit.

In testimony whereof I hereunto affix my signature in the presence of two witnesses.

JACOB RICHARD FRANCIS.
